UNITED STATES PATENT OFFICE.

LEWIS W. CHUBB, OF EDGEWOOD PARK, PENNSYLVANIA, ASSIGNOR TO WESTINGHOUSE ELECTRIC & MANUFACTURING COMPANY, A CORPORATION OF PENNSYLVANIA.

THERMIONIC CONVERTER.

Application filed May 15, 1917. Serial No. 168,678.

My invention relates to electric apparatus of the type wherein an electron blast is produced within a closed container as, for example, in converters and in vacuum lamps, and it has for its object to provide apparatus of the character designated which shall be simple and inexpensive in manufacture and highly effective in operation.

More specifically, the object of my invention is to provide a vacuum-type converter of the hot cathode type which in normal operation shall require no auxiliary heating current, the relative size, location and specific electron emissivities of the different electrodes being such that half cycles of current of one polarity are permitted to pass freely between a given pair of electrodes but, with half cycles of the other polarity, only sufficient current is permitted to pass to maintain the nominal cathode at an electron-emitting temperature.

It is known that a refractory filament composed, for example, of tungsten, may have its specific electron emissivity, at a given temperature, greatly increased by the admixture of a small percentage of foreign substance such, for example, as thorium or thorium oxide. I am not prepared to state whether the additional electrons are derived from the foreign substance or whether there is an action similar to catalysis whereby the foreign substance causes a much more profuse emission from the tungsten itself. Furthermore, I am not in a position to state whether the foreign substance as, for example, thoria is active in its combined state or whether it is reduced to the metallic state before performing its electron-modifying function. In the practice of my invention, however, it is unnecessary to be restricted to any specific theory of operation and the above suggestions are merely offered as an aid to the public in understanding my invention.

While material containing thorium gives extremely good results and may well be employed in the practice of my invention, I find that good results may be obtained by employing zirconium or its compounds as, for example, zirconia.

Fig. 1 of the accompanying drawing is a diagrammatic view, partially in section and partially in elevation, of a vacuum-type converter embodying a preferred form of my invention; and Fig. 2 is a similar view of

a modification of the structure shown in Fig. 1.

Vacuum-type converters are well known in which the cathode is formed into a refractory filament which is maintained at incandescence by any suitable means such, for example, as by the passage of auxiliary heating current therethrough. Said incandescent cathodes have in the past been formed, either of refractory elements such, for example, as carbon, platinum, tungsten or molybdenum, or, in certain cases, they have been formed of refractory filaments covered by oxide coatings because of the high electron emissivity of certain refractory oxides.

In the practice of my invention, I prefer to form the cathode from tungsten or molybdenum containing a small admixture of foreign matter, as before mentioned, and by this means I am enabled to obtain an enormous electron discharge with the expenditure of but little energy in heating the electrode. Thus, I am enabled to provide either a very small heating source for the cathode, for a given capacity of converter, or I am enabled to provide a converter of very small dimensions having a very high capacity.

Furthermore, by employing a vacuum-type converter embodying two electrodes having dissimilar electron emissivities at a given temperature, I am enabled to obtain a pronounced rectifying action while maintaining the entire converter apparatus at an extremely high temperature. Thus, the two electrodes may be mounted in close proximity so that each tends to heat the other and no special precautions need be taken to ensure the cooling of the anode as is the case with the ordinary vacuum-type converter. Furthermore, I am enabled to still further conserve the heat in apparatus of the character designated by providing a suitable heat insulating jacket or equivalent means.

I preferably so arrange the size, mounting and relative electron emissivities of the two electrodes that, during half cycles when the nominal cathode or electrode of high emissivity is negative, the electron emission is such that current may freely traverse the device, sufficient of said electrons bombarding the nominal anode to maintain the same at an electron-emitting temperature. During half cycles of the other polarity, the nominal anode functions to a slight degree as a cathode, not only producing a consider-

able number of electrons which bombard the nominal cathode but also permitting the flow of a small amount of reverse current. The joint action of said reverse current flow and of said bombardment is to maintain the nominal cathode at an electron-emitting temperature during said second-mentioned half cycles, thus permitting the entire device to operate continuously with no source of auxiliary heating current for either of the filaments. While I recognize that the flow of reverse current is, in general undesirable, nevertheless, with many types of load, such, for example, as in battery charging, the effect of the small amount of reverse current flow which is necessary may be disregarded.

Referring to the drawing for a more detailed understanding of my invention, I show a vacuum-type converter at 1 comprising a highly evacuated container 2 supplied with an anode 3 and with a cathode 4. The anode 3 may either be a mass of refractory material such, for example, as carbon or tungsten or it may take the form of a filament of tungsten, as shown. The cathode 4 is in the form of a closely wound filament of tungsten-thorium or tungsten-zirconium mixture or a tungsten filament coated with thorium or zirconium in any desired manner. The anode 3 may be heated by a suitable auxiliary source 5 and, in like manner, the anode 4 may be heated by a suitable auxiliary source 6. An alternating electromotive force is impressed between the electrodes 3 and 4 by any suitable means such, for example, as the secondary winding 7 of a transformer 8 having a primary winding 9 energized from suitable alternating-current mains. A load 40 demanding unidirectional current is shown at 10.

Having thus described the arrangement of a system embodying my invention, the operation is as follows. Upon energizing the transformer 8 and closing the circuits from the auxiliary current sources 5 and 6, an alternating electromotive force, is impressed between the two electrodes and said electrodes are raised to incandescence. The vastly more profuse emission of electrons from the cathode than from the anode 3 permits the free passage of current from the anode 3 to the cathode 4 but the lack of current carriers greatly hinders the flow of current in the opposite direction.

Having initiated operation in this manner, the flow of auxiliary heating current may be prevented and the device will continue to operate, obtaining its entire heating action from the alternating-current supply as has been hereinbefore fully described.

While I have shown the anode 3 in the form of a heated filament, it is obvious that the device will be operable were no heat supplied to said filament or if the anode were

given the form of a cup or sphere as is usual.

Referring to the form of my invention shown in Fig. 2, a container 2 is provided with an anode 3, in the form of a centrally disposed coil, and with a cathode 4 in the form of a straight filament axially disposed within the coiled anode 3. The electrodes 3 and 4 are formed respectively of tungsten and of tungsten alloy as in the structure of Fig. 1. Said electrodes may be initially heated from suitable current sources 5 and 6 through switches 11 and 12. Energy for the operation of the converter is derived from a transformer 8. The container 2 may be surrounded with any suitable heat-insulating means, such, for example, as a fibrous layer 13. In operation, the switches 11 and 12 are first closed, raising the respective electrodes to incandescence and load current then flows from the secondary winding 7. A small portion of each of alternate current waves flows from the electrode 4 as an anode to the electrode 3 as a cathode and substantially all portions of the remaining current waves flow from the electrode 3 as an anode to the electrode 4 as a cathode. Each electrode, when operating as a cathode, bombards the other one. When the electrode 3 is a cathode and the electrode 4 is an anode, there are but relatively few electrons emitted but the electrode 4, by reason of its centrally focal position, is sufficiently heated thereby to maintain its incandescence. When the electrode 4 is a cathode and the electrode 3 is an anode, the profuse electron emission of the electrode 4 is ample to adequately heat the surrounding electrode 3. The heat insulating layer 13 conserves a large portion of the heat generated in the converter and aids in maintaining the respective electrodes at a high temperature. Thus, after the device has been brought into operation, the switches 11 and 12 may be opened and the respective electrodes thereafter maintain a suitable operating temperature solely by virtue of the heat produced by the flow of load current.

Not only is my invention applicable to converters of the character designated but it may also be used with any form of apparatus embodying pure electron emission such, for example, as certain forms of X-ray tubes and of lamps wherein the light source is a refractory body maintained at incandescence by electron bombardment such, for example, as shown in my copending application, Serial No. 129,980, filed Nov. 7, 1916, and assigned to the Westinghouse Electric & Manufacturing Company.

While I have shown my invention in its preferred form, it will be obvious to those skilled in the art that it is susceptible of various minor changes and modifications without departing from the spirit thereof

and I desire, therefore, that only such limitations shall be placed thereupon as are imposed by the prior art or as are indicated in the appended claims.

5 I claim as my invention:

1. In vacuum-type electric apparatus, the combination with an electrode having a relatively low electron emissivity when heated to incandescence, of a filamentary electrode having a relatively high electron emissivity when heated to incandescence, means for maintaining both of said electrodes at incandescence, and means for applying an alternating electromotive force between said electrodes.

2. In vacuum-type electric apparatus, the combination with an electrode composed of a refractory metal having a relatively low electron emissivity when heated to incandescence, of an electrode composed of a metallic mixture having a relatively high electron emissivity when heated to incandescence, means for maintaining both of said electrodes at incandescence, and means for applying an alternating electromotive force between said electrodes.

3. In vacuum-type electric apparatus, the combination with a filamentary electrode composed of a refractory metal having a relatively low electron emissivity when heated to incandescence, of an electrode composed of a zirconium bearing body having a relatively high electron emissivity when heated to incandescence, means for maintaining both of said electrodes at incandescence, and means for applying an alternating electromotive force between said electrodes.

4. In vacuum-type electric apparatus, the combination with a filamentary electrode composed of a refractory metal having a relatively low electron emissivity when heated to incandescence, of an electrode composed of a tungsten-zirconium mixture, means for maintaining both of said electrodes at incandescence, and means for applying an alternating electromotive force between said electrodes.

5. A vacuum-type converter embodying two electrodes having a different electron emissivity when equally heated and means for heating both of said electrodes.

6. The method of operating a vacuum-type converter from a source of alternating current, said converter embodying two electrodes, which comprises permitting free passage to arc current therethrough during half cycles of said source of alternating current of one polarity and permitting passage of only sufficient arc current during half cycles of said source of alternating current of the other polarity to maintain said device in an operative condition.

7. The method of operating a vacuum-

type converter from a source of alternating current, said converter embodying two electrodes, which comprises generating sufficient electrons therein during half-cycles of one polarity to permit the free flow of arc current therethrough, and generating only sufficient electrons therein during half cycles of the other polarity to permit the flow of that amount of arc current necessary to maintain the nominal cathode at an electron-emitting temperature.

8. In vacuum-type electric apparatus, the combination with a nominal cathode, of a nominal anode, connections from said electrodes to the respective terminals of a source of alternating current, and means permitting the flow of only sufficient arc current through the apparatus when said nominal cathode is positive to maintain said electrode at an electron-emitting temperature, said device permitting the free passage of arc current when said nominal cathode is negative in polarity.

9. In vacuum-type electric apparatus, the combination with a nominal cathode composed of material of relatively high specific electron emissivity, of a nominal anode of relatively low specific electron emissivity, and connections from said electrodes to the respective terminals of a source of alternating current, the electron emission of the said nominal cathode when negative being sufficient to permit the passage of substantially the entire current wave and the electron emission of said nominal anode, when negative, being only sufficient to maintain said nominal cathode at an electron-emitting temperature by the joint effect of electron bombardment and of reverse load current.

10. In vacuum-type electric apparatus, the combination with a closed container, of two electrodes therein composed of substances of differing specific electron emissivities at a given temperature and connections from said electrodes to the respective terminals of a source of alternating current, the relative size and emissivities of the two electrodes being such that during half cycles when the electrode of high emissivity is negative, substantially all the current is permitted to pass, bombarding the electrode of low emissivity only enough to maintain said electrode at an electron-emitting temperature, and during the alternate half cycles, only sufficient electrons are emitted by the electrode of low emissivity to cause such current flow and electron bombardment as to maintain the electrode of high emissivity at an electron-emitting temperature.

11. In a vacuum-type electric apparatus, the combination with an electrode having relatively low electron emissivity, of a filamentary electrode having a relatively high electron emissivity, means for maintaining

- both of said electrodes in electron-emitting condition, and means for applying an alternating electromotive force between said electrodes.
12. A vacuum-type converter embodying two electrodes having different electron-emission characteristics and means for maintaining each of said electrodes in an electron emitting condition.
- 10 13. A vacuum-type converter embodying two electrodes having different electron-emissivity characteristics and permitting alternating current to pass therebetween in both directions, but to a different degree whereby said electrodes are kept heated to 15 electron-emitting temperatures.
14. A vacuum-type converter comprising two electrodes of different electron-emitting properties and means for impressing an alternating potential therebetween to 20 cause a large current flow in one direction and a small current flow in the other direction, whereby a net unidirectional current is obtained.

In testimony whereof, I have hereunto 25 subscribed my name this 27th day of April 1917.

LEWIS W. CHUBB.
